UNITED STATES PATENT OFFICE.

CHARLES O. JOHNSON, OF WORCESTER, MASSACHUSETTS.

APPARATUS FOR DRAWING AND STRAIGHTENING WIRE.

1,338,453.

Specification of Letters Patent. Patented Apr. 27, 1920.

Application filed April 23, 1919. Serial No. 292,089.

To all whom it may concern:

Be it known that I, CHARLES O. JOHNSON, citizen of the United States, residing at 22 Lakewood street, Worcester, in the county 5 of Worcester and State of Massachusetts, have invented a new and useful Apparatus for Drawing and Straightening Wire, of which the following is a specification.

This invention relates to an apparatus 10 for drawing and straightening very fine wire.

The general method of drawing and straightening fine wire is to draw it and coil it on a block in one operation; then take 15 the coil from the block, place it on a reel, lubricate it and run it from the reel through a straightener and on to a block.

I have discovered that wire of this kind can be drawn, lubricated, straightened and 20 coiled all in one operation and at many times higher velocity than is possible by the methods hitherto used, and that is the object of this invention.

Reference is to be had to the accompanying drawing which is a longitudinal sectional view of a portion of a wire drawing machine constructed in accordance with this invention and partly diagrammatical.

In order to accomplish the above specified 30 results the wire is drawn from the last draw head 10 of any ordinary continuous wire drawing machine through a die in a die holder 11, and on a rotary carrier 12. The wire is wound around this carrier which 35 pulls it through the die. This carrier supplies the wire to an ordinary wire pin straightener 13 and in passing to it the wire receives an oil bath from an oil receptacle 14 and then passes to the ordinary 40 block 15 which may be of any desired diameter. The carrier 12 and the block 15 in accordance with this invention must be geared up in such a manner as to give them the same surface velocity substantially. This 45 is done by properly proportioning the pulleys 16 and 17 which receive power from the driving shaft 18. This drive shaft 18 drives the carrier 12 through bevel gears or other gearing as may be desired.

50 In this way although the block 15 pulls the wire through the straightener it has no function to perform but the straightening and coiling and causes no stress on the wire between the straightener and the carrier.

55 As is shown an ordinary pin straightener may be used. In this way the process of

drawing and straightening of finest wire is greatly simplified and such wire can be drawn and straightened at increased speed which improves the straightness of the wire 60 and the operation can be performed without the usual breakages. This is an important practical advance in this industry.

Although I have illustrated and described only a single form of the invention I am 65 aware of the fact that modifications can be made therein by any person skilled in the art without departing from the scope of the invention as expressed in the claims. Therefore I do not wish to be limited to 70 all the details of construction or to the specific form of drawing machine herein shown and described, but what I do claim is:—

1. In an apparatus for straightening fine wire, the combination with a carrier for 75 receiving the wire and passing it on, and a block on which the wire is wound, of a straightener between them and means for operating the carrier and block at such a ratio as to eliminate all strain on the wire 80 between the straightener and carrier and keep the wire taut.

2. In an apparatus for straightening fine wire, the combination with a rotary carrier for receiving the wire and passing it on, 85 and a block on which the wire is wound, of a straightener between them and means for rotating the carrier and block at the same surface velocity to prevent the application of strain to the wire before it enters the 90 straightener.

3. In an apparatus for straightening fine wire, the combination of a rotary carrier for receiving the wire and passing it on, a block on which the wire is wound, a straightener between them, means for rotating the carrier and block at such a ratio as to eliminate all strain on the wire between the straightener and carrier, and a wick for applying oil to the wire before it enters the 100 straightener.

4. A process of straightening wire in one continuous operation, consisting in passing the wire from a rotary carrier on a wire drawing machine through an oil bath without stress on the wire, then through a pin straightener on to a drum of any desired size substantially as herein described. 105

5. In an apparatus for straightening fine wire, the combination of a rotary carrier 110 for drawing the wire through a die and passing it on, a block on which the wire is

wound, a pin straightener between the block and the carrier, means for lubricating the wire between the carrier and the straightener, means for rotating the block and the carrier at such a ratio as to eliminate all strain on the wire between the straightener and the carrier.

6. In an apparatus for straightening fine wire in one continuous operation and at a high velocity, the combination with a rotary carrier for drawing the wire through a die and passing it on and a block on which the wire is wound, of a pin straightener between them, means for application of oil to the wire between the carrier and straightener, and means for rotating the carrier and the block at the same surface velocity to prevent strain on the wire between the carrier and the straightener.

7. In an apparatus for straightening fine wire in one continuous operation, the combi-

nation with a rotary carrier for receiving the wire from a die and passing it on, of a block on which the wire is wound, a pin-straightener located between the carrier and block, and means for applying a lubricant to the wire between the carrier and the straightener.

8. In an apparatus for straightening fine wire in one continuous operation, the combination with a rotary carrier for receiving the wire from a die and passing it on, a rotary block, means for rotating the carrier and block at the same surface speed to carry the wire in a straight path from one to the other, of a straightener located directly between the carrier and block in such position that the wire passes in a straight line all the way from the carrier to the block.

In testimony whereof I have hereunto af- 40 fixed my signature.

CHARLES O. JOHNSON.
